PROPELLER PITCH ADJUSTING DEVICE

James H. Booth, Detroit, Mich., assignor to
Thompson Products, Inc., Cleveland, Ohio, a
corporation of Ohio

Application December 18, 1944, Serial No. 568,605

2 Claims. (Cl. 170—160.31)

1

This invention relates to an inexpensive device for adjusting members, such as blades, and specifically relates to an easily installed propeller pitch adjusting device.

The invention provides a small compact assembly, rotatable with a propeller hub, for changing the pitch of propeller blades that are rotatably mounted in the hub. The assembly includes fluid pressure-operated means acting on the blades to rotate them in their mountings. Fluid pressure for actuating these means is created by a pump. The pump is actuated by a non-rotatable cam, and this cam is manually actuated by the pilot into and out of pump-operating position.

According to this invention, the blades of a propeller are mounted for rotation in a propeller hub in such a manner that the aerodynamic force on the blades in operation tends to move them into high pitch. The device of this invention is contained in the hub of the propeller and, when the cam is moved into position for actuating the pump of the device which rotates with the propeller hub, the hydraulic pressure generated by the pump will move the blades into low pitch against this aero-dynamic force.

In order to cause the aero-dynamic forces on the operating blades to urge the blades into high pitch, the blades are tilted back from their radial rotating axes to move their centers of gravity toward their centers of radial rotation to lessen or negative the centrifugal torsion effect tending to rotate the blade into low pitch and the blades are designed to have their centers of pressure to the front of the centers of radial rotation.

While aero-dynamic force alone can be relied upon to urge the blades into high pitch, it should be understood that this force can be augmented by springs, weights, or the like.

A feature of this invention resides in the provision of a compact hydraulic pressure-operated propeller pitch-changing device that can be readily installed on standard airplane engine mountings.

Another feature of the invention resides in the provision of a self-contained unit in a propeller hub for changing the pitch of blades rotatably mounted in the hub.

Another object of this invention is to provide a hydraulically-operated propeller pitch changer utilizing only minute quantities of oil or other hydraulic fluid.

A further object of the invention is to provide a device which adjusts the positions of rotating blades in accordance with the manually adjusted position of a non-rotatable member.

A still further object of the invention is to provide a propeller pitch-adjusting device wherein a stationary cam actuates a pump for producing pressure to change the pitch of propeller blades.

A still further object of the invention is to pro-

2

vide a propeller pitch-changing device embodying a cam member actuated into and out of operating position by the pilot of the plane and, when in operating position, causing a pump rotatable with the propeller to produce hydraulic pressures for overcoming aero-dynamic forces on the propeller blades to change the pitch of the blades.

Another object of this invention is to provide a propeller pitch-changing device having a pump actuated by a cam and a fluid flow control valve actuated by another cam to operate plungers for moving propeller blades about their radial axes.

Other and further objects of the invention will be apparent to those skilled in the art from the following detailed description of the annexed sheets of drawings which, by way of preferred example, illustrates one embodiment of the invention.

On the drawings:

Figure 1 is a plan view of a propeller mounting according to this invention embodying a propeller pitch changing device according to this invention.

Figure 2 is a front end elevational view of the mounting shown in Figure 1 with parts of the propeller blades omitted.

Figure 3 is a cross-sectional view taken along the line III—III of Figure 1.

Figure 4 is a cross-sectional view taken along the line IV—IV of Figure 1.

Figure 5 is a cross-sectional view taken along the line V—V of Figure 2.

Figure 6 is a cross-sectional view taken along the line VI—VI of Figure 5.

Figure 7 is a cross-sectional view taken along the line VII—VII of Figure 4.

Figure 8 is a plan view taken along the line VIII—VIII of Figure 7.

Figure 9 is a cross-sectional view taken along the line IX—IX of Figure 8.

Figure 10 is a cross-sectional view taken along the line X—X of Figure 8.

Figure 11 is a cross-sectional view taken along the line XI—XI of Figure 8.

Figure 12 is a fragmentary cross-sectional view taken along the line XII—XII of Figure 13.

Figure 13 is a plan view of the ring block taken along the line XIII—XIII of Figure 5.

Figure 14 is a plan view of the cover plate for the ring block taken along the line XIV—XIV of Figure 5.

Figure 15 is a developed diagrammatic view illustrating the operation of the fluid pressure actuated parts of the device of this invention.

As shown on the drawings:

As best shown in Figures 1 and 5, the device of this invention includes a mounting plate 10 for operatively attaching certain parts of the device to an airplane engine 11. The engine 11 has upper and lower boss portions 11a. Brackets 12,

12 carried by the mounting plate 10 straddle each boss portion 11a and a connecting pin or lug 13 secures the brackets to the bosses. The mounting plate 10 has a cylindrical collar portion 10a projecting forwardly from the front end of the engine 11 and this collar portion 10a slidably receives a control member 14 having a cylindrical side wall in engagement with the collar portion 10a and equipped with several sloping slots 15 at spaced intervals therearound as best shown in Figures 3 and 7. These slots 15 receive the heads 16a of bolts 16 which are passed through thickened portions of the collar 10a and secured to the collar by means of nuts 17 as best shown in Figure 3.

The collar 10a has an elongated slot 10b therein and an arm 18 secured on the control member 14 extends through the slot 10b to receive a clevis 19 on the end of a control rod, an operating Bowden wire or the like 20. The control rod 20 passes through an aperture in the mounting plate 10a, as shown in Figure 3, and is directed to the cockpit of the airplane where it can be easily reached for manual actuation by the pilot. Movement of the control rod 20 will swing the arm 18 to rotate the control member 14 in the collar portion 10a. However, since the heads 16a project into the diagonal slots 15 of the control member 14, any rotation of the control member will slide it axially relative to the collar 10a.

The control member has an end face with a cam track 14a thereon and a flat surface 14b surrounding the cam track 14a.

As shown in Figures 1, 5 and 7, a propeller hub casing 21 has a rear end portion freely embracing the collar portion 10a of the mounting plate 10. This casing 21 has diametrically opposed laterally projecting cylindrical socket or sleeve portions 21a which receive the inner ends of propeller blades B.

The hub casing 21, as best shown in Figure 5, has a back wall 21b spaced in front of the mounting plate 10 and extending radially inward to a central boss or hub portion 21c which is mounted on the engine shaft S projecting from the front end of the engine 11. The engine shaft S is preferably tapered to receive the hub portion 21c in wedging relationship, and key means such as K (Figure 4) connect the shaft and hub portion 21c for corotation.

A nut 22 is threaded on the front end of the shaft S to thrust against the end of the portion 21c and hold it on the shaft. This nut is locked against rotation by means of pins such as 23 anchored in the nut and hollow skirt-like end S' of the shaft.

A streamlined nose casing 24 is secured on the front end of the hub casing 21 by means of screws 25 or the like for covering the open front of the casing.

The blades B have their inner ends secured in tapered skirt portions 26a of retainer members 26 which are rotatably mounted on ball bearings 27 in the socket 21a of the hub casing. Nuts 28 threaded on the sockets 21a thrust against the outer race rings of the ball bearings 27 to retain these outer race rings in the socket. The ball of the bearings retain the inner race rings in position and a locking ring 29 retained in a groove of the retainer member 26 thrusts against an inner race ring of one of the bearing assemblies so that the retainer cannot move axially relative to the socket 21a. However, the retainer can rotate freely with the inner race rings of the ball bearings 27. The blades B are thus rotatably

mounted about longitudinal or radial axes such as A illustrated in Figure 1, for changing the pitch of the blades. As explained above, each blade is so tilted with respect to its axis of radial rotation A to negative centrifugal torsion effect tending to rotate the blade into low pitch and has the center P of pressure on the blade forwardly from this axis A so that aerodynamic forces on the blade tend to rotate it into high pitch.

The retainers 26 for the blades B have tail portions 26b extending into the casing 21. These tail portions 26b carry laterally projecting pins 30 and 31 in right angular relation. The pins 31 project into slots 21d of the rear wall 21b of the hub casing 21, as best shown in Figures 4 and 5. Set screws 32 are threaded into the wall 21b to project into opposite sides of the slots 21d and form abutments for the pins 31 thereby limiting the amount of rotation of the blades B about the axes of radial rotation A. These set screws 32 can be adjusted so that the amount of radial rotation of the blade can be controlled to any desired degree. Likewise, the screws can be adjusted so that the desired high pitch and low pitch positions for the blades can be obtained since the setting of screws 32 on one side of the pins 31 will determine the high pitch positions for the blades B while the setting of screws 32 on the other side of the pins 31 will determine the low pitch positions for the blades. If desired springs (not shown) can be used to act on the pins 31 for urging the blades to rotate into high pitch positions, thereby assisting the aerodynamic force which maintains the blades in high pitch positions.

Nuts 33 can be provided on the set screws 32 for locking the same in adjusted position.

As best shown in Figure 5, a ring block 35 is mounted in the hub casing 21 and has a central aperture 35a extending from one end face thereof to receive the end of the hub portion 21c. A shoulder 35b is provided at the bottom of the aperture 35a to thrust against the end of the hub portion 21c. A second aperture 35c extends inwardly from the other end of the ring block 35 to receive the nut 22 freely therein and this aperture 35c has a shoulder 35d at the bottom thereof bottoming a flange 22a of the nut. The ring block 35 is thus secured to the hub 21c. In addition, however, bolts such as 36 are passed through the ring block and threaded into the back wall 21b of the hub 21.

A top cover plate 37 is held on the ring block by means of cap screws such as 38 threaded into the block. A bottom cover 39 is held on the bottom of the ring block by means of bolts such as 40.

As best shown in Figure 12, the ring block 35 carries an oil tank or casing 41 in an aperture thereof, and this casing 41 projects beyond the bottom cover 39 into the space between the bottom cover and the end wall 21b of the hub 21. A plunger 42 is slidably mounted in the casing 41 and this plunger 42 has a head 42a at one end thereof slidably engaging the walls of the casing, together with a reduced-diameter hollow shank portion 42b projecting toward the other end of the casing in spaced relation inward from the casing wall. The head 42a has vents 43 therethrough connecting the space in the tank between the head and end wall of the tank with the space in the tank surrounding the shank 42b. A seal 44 is carried by the shank 42b and slidably engages the wall of the tank in sealing relation therewith. A coil spring 45 is contained in the

shank 42b to urge the plunger 42 toward the closed end of the tank. A plug 46 is threaded into the cover plate 37 for bottoming the coil spring 45.

Oil or other hydraulic fluid in the tank 41 is thus always maintained under spring pressure, so that air can never be delivered to the system in the event of leakage of oil. For example, as oil might leak out of the system, or contract due to temperature changes, the spring 45 will urge the plunger member 42 down toward the closed bottom of the tank for decreasing the size of the tank, since the seal 44 will render ineffective any portion of the tank interior lying between it and the open end of the tank. The oil is vented from the closed end portion of the tank through the holes 43 into the space surrounding the shank portion 42b of the plunger from which the oil is fed into the system.

When it is desired to fill the system with oil or other operating fluid, the plug 46 and spring 45 are removed, a rod is threaded into the threaded well portion of the plunger, and the plunger is retracted toward the cover plate 37. Both plugs shown in Figure 15 are removed from the cover plate 37 and oil or other fluid is poured into one plug aperture while the other plug aperture acts as an air vent. The retracted plunger allows the tank 41 to be filled with oil. As shown in Figure 7, a pump assembly 47 is provided in another aperture of the ring block 35. This pump assembly includes a piston 48 slidably operating in the bore of a block 49 contained in the aperture and connected to a carrier 50 for a roller 51 adapted to ride on the cam track 14a. The carrier 50 is slidably mounted in a sleeve 52 carried by the block 35 and projecting therefrom into the space between the block and the back wall 21b of the hub. A coil spring 53 acts on the carrier 50 to urge it outward from the sleeve 52 and seat its flange 50a on a shoulder 52a provided in the sleeve. The cam track 14a on which the roller 51 rides reciprocates the piston 48 to pump fluid supplied thereto from the tank 41 as will be more fully hereinafter described.

As shown in Figures 12 and 13, the ring block 35 has diametrically opposed apertures therethrough each containing a plunger assembly 55. Each plunger assembly 55, as shown in Figure 12, includes a sleeve 56 seated in the aperture and slidably receiving therein a plunger member 57 carrying a seal 58 in sliding sealing engagement with the sleeve. The plunger member has a button end portion 57a projecting through an aperture in the bottom plate 39 of the block into the space between the block and the back wall 21b of the hub. As shown in Figure 5, this button end 57a of the plunger acts on the pin 30 to rotate the blade B thereby changing the pitch of the blade.

As shown in Figures 7 to 11, a valve assembly 60 is provided in another aperture of the block ring 35. This assembly 60 includes a block 61 disposed in the aperture of the ring block 35 and slidably receiving a dumbbell type valve 62. The valve 62 has a stem projecting through the bottom plate 39 of the ring block and attached to a carrier 63 for a roller 64 adapted to ride on the track portion 14b of the control member 14. A sleeve 65 slidably receives the carrier 63 and is carried by the ring block 35. A spring 66 is provided in the carrier 63 and acts thereagainst to urge the carrier outwardly from the ring block to abut a flange 63a thereof against a shoulder 65a of the sleeve.

Three check valve assemblies are provided in

the block 60 symmetrically around the central dumbbell valve 62 as illustrated in Figures 8 to 11. As shown in Figures 9, 14 and 15, the cover plate 37 has a groove therein providing a passageway 69 to the valve seat 70 of the first valve assembly. A ball 71 is pressed by a spring 72 to seat against the seat 70. Fluid under pressure of the pump is sufficient to unseat the ball 71 so that the fluid can flow through the passageway 73 into another groove 74 in the cover 37. This groove 74 has communication with the seat 75 of the second valve assembly, with the pump chamber of pump assembly 47, and with the third valve assembly.

15 As shown, oil can be drawn from tank 41 on the suction stroke of the piston 48 to flow through check valve 70 into passage 73 and groove 74. Pressured oil can be by-passed from plunger 48 through check valve 76 into passages 78 and 79

20 back to the tank, as hereinafter described. In Figure 15 the passageway 79 is shown diagrammatically as being in the ring block 35 whereas, as shown in Figures 10 and 14, this passageway 79 is actually a groove in the cover 37 communicating with groove passageway 69. The connected grooves 79 and 69 by-pass the oil from passage 78 back to the tank, while the groove 69 also supplies oil to the pump through check valve 70.

25 30 Fluid can also flow from the groove 74 into a passage 80 to the valve seat 81 of the third valve assembly where it can force the ball 82 off of the seat against the pressure of the spring 83 and then flow into a passageway or groove in the cover. The groove 84 communicates with a passageway 85 in the ring block, which passageway communicates with a groove 86 around the sleeve 56 of the plunger assembly to a passageway 87 in the ring block connected through a

35 40 passageway 88 to the chamber of the dumbbell valve. The valve 62 can connect the passageway 88 with a passageway 90 communicating through a groove 91 in the cover plate with the ends of both plungers 55 to move the plungers against 45 the pins 30 for rotating the blades into low pitch. Alternately, the valve 62 can block the passageway 88 and join the groove 91 and passageway 90 with a passageway 92. This passageway 92 in the ring block 35 communicates with a groove 93 50 around the sleeve 56 of the second plunger assembly 55 and the groove 93, in turn, communicates with a passageway 94 back to the oil tank.

Operation of the device

55 The propeller pitch-changing device of this invention includes a hub assembly rotatably carrying propeller blades to turn about radial axes from high pitch to low pitch positions, the limits of which are determined by the positions and settings of the set screws 32. In normal 60 operation, the aerodynamic and other forces on the propeller blades maintain the blades in high pitch position because the blades are arranged to have their centers of pressure forwardly of their axes of radial rotation.

65 When it is desired to rotate the blades about their axes of radial rotation into low pitch position, the pilot merely pulls the Bowden wire or control rod 20. This rotates the control member 14 in the mounting plate 10, and rotation of the control member throws it axially forward because the bolt heads 16a seat in tapered slots 15.

70 75 The control member has an inclined cam track or ramp 14a on its front face together with a flat surface around this cam track. When the

control member is moved forwardly the cam track 14a engages the roller 51 of the pump assembly 41 while the surface 14b around the cam track engages the roller 64 of the valve assembly 30.

The cam track 14a reciprocates the plunger 48 of the pump and causes the pump to pump oil from the tank 41. Thus, on the suction stroke of the pump, oil is drawn in past the check valve 71 and, on the pressure stroke of the pump, the thus drawn-in oil is discharged against the check valve 82. If the pressure is too great, the oil will flow past the check valve 76 back to the tank.

The oil under pressure flows from the check valve 82 into the dumbbell valve-operating chamber and the engagement of the roller 64 of the valve with the surface 14b of the control member moves the valve to a position so that the oil will flow to the ends of the plungers 55 throwing these plungers outwardly against the pins 30 and thus rotating the blades B to low pitch positions as determined by the setting of the set screws 32.

The pump will continue to operate as long as the control member is in its forward position and the roller of the pump is in engagement with the cam track. However, excessive pressures are not developed by the pump since the oil or other hydraulic fluid will recirculate back to the tank through the check valve 75. Only small amounts of hydraulic fluid are necessary. For example, about $\frac{1}{3}$ of a cubic inch of fluid is sufficient.

When it is desired to permit the blades to resume their high pitch position, the Bowden wire or control rod 20 is again actuated by the pilot to rotate the control member 14 in the reverse direction whereupon the screw heads 16a and slots 15 retract the control member to space the cam track 14a away from the roller 51. The spring 66 of the valve assembly moves the dumbbell valve to place the passages 91 and 93 in communication with the passages 92 and 94 back to the tank. The aerodynamic and other forces on the blades are thus sufficient to rotate the blades and the pins 30 will force the plungers 55 back into the ring block 35. The oil in back of these plungers can flow freely through the valve back to the tank.

From the above descriptions it will be clear that the device of this invention is simple, fool-proof, and inexpensive. It can be readily installed on an airplane without the aid of special mounting fixtures since the mounting plate is readily adapted for connection with the conventional airplane engine while the hub will replace the conventional propeller hub.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A propeller pitch-adjusting device comprising a propeller hub having a hollow central portion and radially extending sockets communicating with said central portion, blade-mounting devices rotatably carried in said sockets and having portions projecting into said hollow portion of the hub, pins extending laterally in angular relation from said projecting portions of the blade-mounting devices, set screws threaded in said hub arranged to engage opposite sides of

one set of pins on said blade-mounting devices, hydraulically-operated plungers in said hub arranged to engage the same sides of the other set of pins on said mounting devices for moving said devices to change the pitch of the blades carried thereby, a pump carried by said hub for supplying hydraulic fluid under pressure to said plungers, a tank carried by said hub for supplying hydraulic fluid to said pump, a control valve carried by said hub for selectively connecting said plungers with said pump and said tank, and a shiftable cam mounted adjacent said hub having a cam track for actuating said pump and a surface for moving said valve whereby rotation of the hub and engagement of the pump and valve with the control device will create hydraulic pressure actuating the plungers for changing the pitch of the propeller blades.

2. In an engine including a shaft, a propeller pitch-adjusting device comprising a hollow hub having radially extending sockets, a ring block member carried by said hub in the hollow interior thereof and arranged to surround the engine shaft, said block member having a plurality of recesses therein, plungers slidably mounted in some of said recesses, a control valve mounted in another recess, a pump mounted in still another recess, passageways in said block operatively connecting said plungers, said pump and said control valve for fluid intercommunication, said control valve and said pump having actuating means projecting from said block, propeller blade mounting devices rotatably carried in said sockets and extending into the hollow interior of the hub arranged to be acted on by said plunger portions, and a shiftable cam member arranged to be carried by an aircraft engine adjacent said hub and shifted into engagement with said projecting portions of the pump and control valve to open the valve and reciprocate the pump for supplying fluid under pressure to said plungers to force the plungers outwardly from the ring block against the inwardly projecting portions of the blade mounting devices for rotating said blade mounting devices.
